UNITED STATES PATENT OFFICE.

SAMUEL MAYER, OF NEW YORK, N. Y.

DICTIONARY.

1,328,178.

Specification of Letters Patent. Patented Jan. 13, 1920.

Application filed October 7, 1919. Serial No. 329,171.

To all whom it may concern:

Be it known that I, SAMUEL MAYER, a citizen of the United States, residing at New York, in the county of New York and 5 State of New York, have invented certain new and useful Improvements in Dictionaries, of which the following is a specification.

My invention relates to new and useful 10 improvements in a dictionary and it has for its principal object the provision of a device for taking the place of the book now so commonly in use.

A further object of the invention resides 15 in the provision of a case or cabinet having a plurality of compartments each of which is adapted to receive a casing having a web containing the words of a letter of the alphabet.

20 Another object of the invention resides in the provision of means for operating the various webs containing the different letters of the alphabet.

A still further object resides in the provision of means for selecting the different letters and operating each letter separately.

With these and other objects in view my 25 invention consists in the novel details of construction and arrangement of parts 30 which will be more clearly understood from the following specification and drawings in which:—

Figure 1 is a top plan.

Fig. 2 is a transverse vertical section on 35 the line 2—2 of Fig. 1 looking in the direction of the arrow.

Fig. 3 is a transverse vertical section on the line 3—3 of Fig. 1 looking in the direction of the arrow.

40 Fig. 4 is fragmental detail showing a vertical section through one of the cases containing the web.

Fig. 5 is a section on the line 5—5 of Fig. 4 looking in the direction of the arrow.

45 Fig. 6 is a section on the line 6—6 of Fig. 5 looking in the direction of the arrows and

Fig. 7 is a section on the line 7—7 of Fig. 5 looking in the direction of the arrows.

50 In carrying out my invention I provide a cabinet 1 which is open at the top. This cabinet is divided into a plurality of compartments by means of the longitudinally extending vertical partitions 2. Each 55 partition has a plurality of longitudinally

spaced pins 3 secured to one face thereof, as more particularly illustrated in Fig. 1 of the drawing and for a purpose to be later described.

A longitudinal grooved roller 4 is journaled in each of the compartments formed by the partitions 2 and a gear wheel 5 is secured on one end of each of these rollers as more particularly illustrated in Figs. 1 and 2 of the drawings. Smaller gear 65 wheels 6 are rotatably mounted in the cabinet, beneath the gears 5, and as more particularly illustrated in Fig. 2 of said drawings the small gear wheels 6 mesh with the adjacent gear wheels 5. In other words the 70 gears 5 and 6 go forward to make up a continuous train of gears. A gear wheel 7 is rotatably mounted in the cabinet 1 and as shown more particularly in Fig. 2 of the drawings this gear wheel 7 meshes with the 75 middle gear wheel 5. The shaft 8 upon which the gear 7 is mounted extends outside of one end of the cabinet 1 and has the crank handle 9 secured thereto as more particularly illustrated in Fig. 1 of the drawings. By this arrangement when the handle 9 is rotated the gear wheel 7 in turn will rotate and rotate the middle gear wheel 5. The gears 5 being intermeshed with the 80 gears 6 will allow all of the gears to be 85 rotated in unison and the rollers 4 will therefore be rotated.

A plurality of boxes 10 are adapted to be arranged in the cabinet 1 and will be received in the various compartments in longitudinally spaced relation as more particularly set forth in Fig. 1 of the drawings. The boxes are open at the bottom and provided in the rear walls with the vertically extending elongated openings 11 adapted to receive the pins 3 secured to the face of the partition 2. Each of the boxes 10 is also provided in the top with a glass insert for a purpose to be later described. A shaft 13 is rotatably mounted in each box 100 adjacent the top thereof and a similar shaft 14 is rotatably mounted in each box adjacent the bottom thereof. A collar 15 is secured on each of the shafts, adjacent one end thereof, for a purpose to be later described. A disk 16 is loosely mounted on the outer end of the shaft 13 and has a pawl 17 secured thereto on the inner face and adapted to engage a ratchet wheel 18 which is secured to the shaft. 110

A gear wheel 19 is loosely mounted on the outer end of the shaft 14 and has a pawl 20 pivotally connected to the inner face thereof. This pawl 20 is adapted to engage 5 a ratchet wheel 21 secured upon the shaft 14. A rod 22 connects the disk 16 and gear wheel 19 and acts to operate the same in unison. A web 23 has one end secured to the shaft 13 and the opposite end is secured 10 to the shaft 14. The web is adapted to be wound upon the two shafts and extends over rods or rollers 24 secured adjacent the top of the boxes. The arrangement of the webbing is more particularly brought out 15 in Figs. 4 and 5 of the drawings.

The boxes 10 are, as previously stated, received in the compartments and are vertically adjustable. The pin 3, operating in the slot 11 will limit the movement of the 20 boxes and, as is shown in Fig. 4 of the drawings, when the box is lowered the gear wheel 19 will mesh with the groove roller 4.

Having fully described the detailed construction of my device it is thought that 25 the advantages and mode of use will be clearly understood. As I have stated in the objects of my invention I have constructed the present device so that the present form of dictionary may be done away with. It 30 is a well known fact that in using a large book dictionary considerable trouble is encountered in properly arranging the book and opening it to the desired place. In carrying out my present invention I have 35 provided a cabinet carrying a plurality of boxes. Each box contains a webbing having the words of one letter of the alphabet. The boxes are so arranged that the letters to be looked up may be selected and provision 40 is also made for operating the device to bring the proper word in view beneath the glass insert 12. The boxes will be arranged as more particularly brought out in Figs. 1, 45 3, and 4 of the drawings. Normally the boxes are in raised position. When it is desired to look up a word that box containing the first letter of the word is selected and 50 pressed downwardly until the gear wheel 19 meshes with the groove roller 4. The handle 9 is then rotated and this rotates the gear wheel 7 meshing with the middle gear wheel 5. Through means of the train 55 of gearing the rollers will each be operated and that roller engaging with the gear wheel 19 will operate the gear wheel which in turn will operate the webbing 23. By the connecting bar 22, the pawls 17 and 20, and ratchet wheels 18 and 21, it will be noted 60 that the webbing will be properly fed from one roller to the other. Provision is thus made for the greater rotation of one shaft than the other and the webbing will be properly fed at all times. When the word 65 being looked up comes beneath the glass insert 12 the handle is released and the defi-

nition and spelling of the word may be studied at will. After this has been properly studied the box is then raised and the operation may be repeated at will.

The foregoing description and the drawings have reference to what may be considered the preferred, or approved, form of my invention. It is to be understood that I may make such changes in construction and arrangement and combination of 75 parts, materials, dimensions, etc., as may prove expedient and fall within the scope of the appended claims.

Having fully described my invention what I claim as new and desire to secure by Letters Patent is:—

1. A dictionary comprising a cabinet, a grooved roller rotatably mounted in the cabinet, a vertically adjustable box mounted in the cabinet, an adjustable web secured 85 in the box, and means carried by the box and engaging the grooved roller for operating the web.

2. A dictionary comprising a cabinet, divided into a plurality of compartments, a plurality of vertically adjustable boxes received in each compartment, an adjustable web operating in each box, and means for adjusting each web.

3. A dictionary comprising a cabinet, a 95 plurality of boxes vertically adjustable in the cabinet, an adjustable web secured in each box, and means for adjusting the webs in unison or one web at a time.

4. A dictionary comprising a cabinet divided into a plurality of compartments, a grooved roller rotatably mounted in each compartment, a plurality of boxes mounted in each compartment, an adjustable web secured in each box, and means carried by the 105 boxes and engaging the grooved rollers for operating the webs.

5. A dictionary comprising a cabinet divided into a plurality of compartments, a grooved roller rotatably mounted in each 110 compartment, a plurality of vertically adjustable boxes arranged in each compartment, a shaft rotatably mounted adjacent the upper end of each box, a shaft rotatably mounted adjacent the lower end of each box, 115 a gear wheel secured on the lower shaft and adapted to be brought into mesh with one of the grooved rollers, and a web secured to and wound upon the shafts.

6. A dictionary comprising a cabinet divided into a plurality of compartments, a grooved roller rotatably mounted in each compartment, a train of gears connecting the rollers, means for operating the gears, a plurality of boxes vertically adjustable in each compartment, a shaft rotatably mounted adjacent the upper end of each box, a shaft rotatably mounted adjacent the lower end of each box, a disk rotatably mounted on the upper shaft, a ratchet wheel secured 125 130

to the shaft, a pawl pivotally mounted on the disk and adapted to engage the ratchet wheel, a ratchet wheel secured to the lower shaft, a gear wheel rotatably mounted on 5 the lower shaft and adapted to engage one of the grooved rollers, a pawl pivotally connected to the gear wheel and adapted to engage the ratchet wheel, a bar connecting the

disk and gear wheel, and a web secured to and wound upon the shafts. 10

In testimony whereof I affix my signature in presence of two witnesses.

SAMUEL MAYER.
